UNITED STATES PATENT OFFICE.

JAMES H. HITCHINGS, OF SAN FRANCISCO, CALIFORNIA.

DESIGN FOR SATCHEL.

Specification forming part of Design No. 6,014, dated July 30, 1872.

Specification describing a Design (or designs) for Satchels, invented by JAMES H. HITCHINGS, of the city and county of San Francisco, State of California.

The nature of my design is fully represented in the accompanying drawing, to which reference is made.

A represents the satchel, having a strap, S, a flap or cover, F, and large and small pockets or receptacles P and P', respectively. The front of this satchel A is ornamented with a design or designs, D and D'. The top one, D, is on the flap F, and represents the number of the satchel, and the particular State in which such satchel may be used, with a central figure of an eagle grasping and defending the United States flag. The bottom design D' is suggestive of the use to which such satchel may be put to by representing a country school-house with boys on their way to school.

I am aware that a form of satchel similar to this is not new, also the figure of the eagle grasping the flags in the design D, and I do not claim them. The distinctive character of my design is found in the numbering of the satchel so as to prevent an interchange of the same among school children, and the affixing of the State as stamped in design D, and also the representation of the school scene, as shown in design D', on the lower portion of the satchel.

What I claim as my invention is—

The designs D D' for the ornamentation of a satchel, substantially in the manner shown and described.

JAMES H. HITCHINGS.
